CLAIM

The ornamental design for a designer hat with double strap enclosure, as shown and described.

DESCRIPTION

FIG. 1 is a perspective view of a designer hat with double strap enclosure showing my new design;

FIG. 2 is a front view thereof;

FIG. 3 is a back view thereof;

FIG. 4 is a side view thereof;

FIG. 5 is a another side view thereof;

FIG. 6 is a top view thereof;

FIG. 7 is a bottom view thereof; and,

FIG. 8 is another perspective view thereof.

The broken lines on claimed surfaces depict claimed stitching. The broken lines showing a human form in FIG. 8 depict environment and form no part of the claim.

1 Claim, 8 Drawing Sheets
